UNITED STATES PATENT OFFICE

2,377,367

WINDING MACHINE

Winthrop L. Perry and Edward J. Abbott, Wilton,
N. H., assignors to Abbott Machine Company,
Wilton, N. H., a corporation of New Hampshire

Application March 31, 1941, Serial No. 386,136

44 Claims. (Cl. 242—32)

This invention relates to textile machines and is especially applicable to winding machines of the type covered by United States Patent No. 2,160,810. Among the several objects of invention are to improve such machines in regard to the taking and supplying of fresh bobbins to be wound; to provide improved constructions for the electric connections and controls; to provide improved forms of traversing thread guide mechanism adapted for automatic control; to provide improved mechanism for imparting the desired reciprocating movement to the thread guide; to provide improved mechanism for manipulating the bobbin-holding centers, thread guide and other parts of the winding unit in the automatic changing of the winding bobbin; to provide for segregating the wound products of selected ones or groups of the winding units, and to provide improved mechanism for winding a bunch or similar reserve of yarn at the beginning of winding of a bobbin. Other objects and advantages of the invention will be apparent from this specification and its drawings wherein the invention is explained by way of example by reference to two embodiments thereof.

In the drawings:

Fig. 1 is a front elevation of the right hand portion of a machine according to the present invention with all of the winding units except one omitted and certain other parts omitted;

Fig. 2 is a plan of the left hand portion of the machine of Fig. 1;

Fig. 3 is a vertical section on a larger scale showing the reel for the electric conductors which carry current to the travelling winding units;

Fig. 4 is a left end elevation of the machine of Fig. 1 showing one of the winding units in side view;

Fig. 5 is a fragmentary view showing the upper portion of the travelling winding unit of Fig. 4 to a larger scale;

Fig. 6 is a front view of the upper portion of the winding unit of Fig. 5;

Fig. 7 is a plan view to a slightly smaller scale of the winding unit of Fig. 5.

Fig. 7^a is a detail view taken on the line 7^a—7^a of Fig. 7;

Fig. 7^b is a bottom view of the cover of the cam mechanism of Fig. 7 and a portion of the traverse bar.

Fig. 8 is a vertical sectional view on the line 8—8 of Fig. 7, showing the thread guide assembly;

Fig. 9 is a fragmentary vertical sectional view of the bobbin hopper, taken on the line 9—9 of

Fig. 2 and showing the vertically-movable plates of the bobbin hopper in end elevation;

Fig. 10 is a side view of the pair of vertically-movable plates of the bobbin hopper;

Fig. 11 is a detail, in horizontal section on the line 11—11 of Fig. 1 showing one of the guides for the vertically-movable plates of the bobbin hopper;

Fig. 12 is a diagrammatic plan view of the yarn-cutting scissors;

Figs. 13 to 23 illustrate a modified form of machine many of the parts of which are similar to that of Figs. 1 to 12;

Fig. 13 is a vertical sectional view through a winding machine of the general type shown in Figs. 1 to 12, showing in elevation a modified form of bobbin hopper, bobbin magazine and mechanism for delivering bobbins from the hopper to the magazine;

Fig. 14 is a diagrammatic view in the nature of a plan showing a portion of the track, bobbin hopper, bobbin-feeding mechanism, and certain actuating mechanism of the modified form of the machine;

Fig. 15 is a view similar to Fig. 5 showing the upper portions of the travelling unit of the modified form of machine and a portion of the bobbin feeding mechanism;

Fig. 16 is a view similar to Fig. 6 comprising a front view of the upper portion of the winding unit of the modified form of machine;

Fig. 17 is a fragmentary view taken from the rear of Fig. 16 showing brush-actuating mechanism for the modified form of machine;

Fig. 18 is a view similar to Fig. 7 comprising a plan view of a winding unit of the modified form of machine;

Fig. 18^a is a perspective view of a yarn-guiding cam-like plow plate and cutting element of the unit of Fig. 18;

Fig. 19 is a vertical sectional view on the line 19—19 of Fig. 18;

Fig. 20 is a vertical sectional view on the line 20—20 of Fig. 19;

Fig. 21 is a diagrammatic view taken from the point of view of Fig. 13 but to a larger scale and with parts of the passing winding unit omitted, and showing the manner of delivery of empty bobbins to the travelling winding units;

Fig. 22 is a fragmentary vertical sectional view on the line 22—22 of Fig. 21; and

Fig. 23 is a fragmentary vertical sectional view on the line 23—23 of Fig. 13.

Fig. 24 is a diagrammatic plan view of the thread-guide assembly of the device of Figs. 1

to 12 in the act of winding a reserve bunch, and Fig. 25 is a diagrammatic view of a bobbin with the bunch wound thereon;

Fig. 26 is a view similar to Fig. 24 of the thread-guide assembly of the device of Figs. 13 to 23 in the act of winding a reserve bunch, and Fig. 27 is a diagrammatic view of a bobbin with the bunch wound thereon by the device of Fig. 26.

As in Patent No. 2,160,810, a suitable guideway for the travelling units of the machine may be comprised of upper and lower rails 11 and 12 each disposed in opposite straight and semi-circular runs (Fig. 2) and supported by any suitable transverse frame sections 13 and longitudinal end frame sections 14 (Fig. 1). Likewise as in Patent No. 2,160,810 a suitable means for conveying the travelling units around the machine may comprise an endless chain 14' running on sprocket wheels 15 at opposite ends of the machine, the sprocket wheel 15 which is shown in Fig. 1 being driven through suitable connections from an electric motor 20.

Referring particularly to Figs. 5 to 8, the head portion of a winding unit may for example comprise a frame element 40 extending as shown in Figs. 6 and 7 generally lengthwise of the upper rail 11 and carrying suitable rollers 41, 42, 43, 43 and 44, 44 adapted to guide the unit along this upper rail. A generally vertical frame element 50 extending from the upper frame element 40 down to the lower rail 12 carries a suitable support 52 for the unwinding supply package 53 and a suitable support 56 for the guide wires 57 and tension device 58 which may for example be constructed as shown in Patent No. 1,965,363, dated July 3, 1934.

Referring to Figs. 5 and 7, a hollow driving head 60 adapted to receive the base of the winding bobbin and having a serrated rim 61 is driven through a shaft 62 from an electric motor indicated generally at 63. A reciprocating traverse bar 66 is driven with a short stroke of traverse (considerably less in length than the final length of the wound bobbin) through cam mechanism also operated by the motor 63. As shown in Fig. 7 the motor shaft 62 carries a worm 10 meshing with and driving a cam wheel 72 through teeth 73 on the periphery thereof. The cam wheel 72 is provided with a double-throw cam groove 74 of generally double heart shape, the shape of this groove and speed and direction of rotation of the cam preferably being such that the traverse bar 66 is driven faster on its outgoing stroke toward the tip of the bobbin than on its return stroke toward the base of the bobbin. For example, the speed of the traverse bar on its outgoing stroke may be such that the winding bobbin makes ten revolutions during the outgoing stroke of traverse, and on its return stroke the winding bobbin makes twenty revolutions. Moreover, the shapes of the two heart-shaped portions of the cam are preferably such as to provide a variation in length of traverse stroke of the traverse bar. As shown in the preferred form of cam this variation in length of stroke takes place with each stroke thus insuring that the end of no stroke of traverse will exactly coincide with the next previous similarly directed stroke. Thus in the preferred machine the traverse bar moves through a cycle of traverse as follows: from base toward tip of bobbin, 1 $\frac{1}{2}$ inches; from tip toward base of bobbin, 1 $\frac{1}{2}$ inches; from base toward tip of bobbin, 1 $\frac{1}{2}$ inches; from tip toward base of bobbin 1 $\frac{1}{2}$ inches. Obviously these figures are merely illustrative of a sequence of traverse strokes adapted to avoid

coincidence of the end of one stroke with the end of the next previous similarly directed stroke. A link 80 pivotally mounted at 81 carries a cam follower 83 riding in the groove 74, and serving to oscillate this link 80. A slot 88 in the link receives a follower 89 carried by the traverse bar 66, thus transmitting the desired reciprocating motion to the traverse bar.

Preferably the cam 72, worm 10, and shaft 62 are mounted in a casing 90 secured to the frame element 40, this casing having integral therewith a cup-shaped portion 90^a surrounding and holding one end of the motor 63. The traverse bar 66 extends into the casing 90 through a slot 92 (Figs. 7 and 7^a). The upper portion of the casing 90 over the cam 72 is covered by a detachable cover plate 90^b into which the pivot 81 fits, the cover plate 90^b constituting a guiding surface for the transverse bar 66 as shown in Figs. 7^a and 7^b.

The tip end of the winding bobbin is held during the winding in a hollow center 100 which is rotatably mounted in a tail stock 101. Tail stock 101 is carried by a rod 102 (Fig. 5) which is slidably mounted in a sleeve 103 projecting from the frame element 40, rod 102 being provided with a flange 104 adapted to prevent its rotation in sleeve 103. Rod 102 extends through the opposite side of the frame element 40 and there is acted upon by a spring 105 so as to urge the tail stock 101 toward the left in Figs. 3 and 7 and normally retain the winding bobbin between the centers 60 and 100. A reduced diameter portion 107 on the inner end of rod 102 is adapted to be operated on by a stationary cam 110 to force the tail stock 101 outwardly away from the winding bobbin thereby to discharge the bobbin from winding position when this cam surface 110 is encountered, as more fully described below.

On the traverse bar 66 there is loosely mounted a bracket having opposite legs 114 and 115 slidably on the traverse bar and connected by a portion 116 parallel with the traverse bar. The inner end of this bracket is provided with a flattened extension 117 slidably resting on a shelf-like support 120.

The electric motor 63 is controlled through a mercury switch 130 which is secured at the under side of a generally U-shaped piece 131 which is pivotally mounted at 132. Referring to Fig. 7, a latch 135, pivotally connected to one leg of the U-shaped piece 131, normally overlies the extension 117 from the bracket 116 so that in normal running the mercury switch is retained closed. Shifting of the bracket 116 to the right in Fig. 7 (which will result either from breakage of the yarn or completion of the package as explained below) removes the extension 117 from beneath the latch 135 and allows the mercury switch to drop and open. In addition to controlling this mercury switch the bracket 116 serves as a guide for the traversing thread guide as will now be explained.

The thread guide assembly includes a plate 140 shown especially in Figs. 6, 7, and 8. A thread-guide arm 144 is pivotally mounted on the under side of the plate 140 at 141 and extends over across the winding package to the opposite side thereof. At this extremity, the thread guide arm 144 carries an eye 145. The yarn running upwardly from the yarn detector 146 (described below) runs upwardly through this eye 145, thence over the arm 144 to another eye 149 thence downwardly onto the winding package. A yoke 150, of which the opposite vertical legs 151 have a loose fit on the traverse rod 66, underlies the plate 140 and thread

guide arm 144, and is bolted to the plate 140. Yoke 150 carries an integral extension 153 which rides upon the longitudinal bracket portion 116 and holds the thread guide against turning around the traverse rod 66. A second yoke 154 within the yoke 150 and also having a loose fit on the traverse rod 66, has one arm 155 which extends out over the winding package constituting a feeler for the yarn on the package, and another arm 156 which extends out over the bracket portion 116 and has a downturned edge portion 157. A spring 158 interposed between the yokes 150 and 154 causes them to grip the traverse rod 66 frictionally.

The bracket portion 116 carries a blade-like element 160 clamped thereto and provided with teeth 161 on its upper edge, these teeth having an inclination such that the downturned edge portion 157 rides easily over them while the thread guide is moving outwardly away from the base of the bobbin, but such as to catch and hold the downturned edge portion 157 when it is pressed against the teeth during motion of the thread guide toward the base of the bobbin. It will be understood that the downturned edge portion 157 can ride over the teeth without engaging them, and that it does so until the feeler 155 rises in response to contact with the yarn on the bobbin. Thereupon the downturned edge portion 157 catches against one of the teeth 161 and detains the thread guide assembly against moving farther toward the base of the bobbin. The effect of this is to allow the reciprocating traverse rod 66 to slip with respect to the thread guide assembly until the traverse rod reaches the inner end of its stroke and reverses direction whereupon the downturned edge portion 157 disengages the teeth and the traverse assembly resumes its reciprocating motion. By this means the traverse assembly is advanced axially with respect to the traverse rod 66 in accordance with the growth of the package.

The blade-like element 160 carrying the teeth 161 is also adapted to serve as a forming plate to control the shape of the bobbin wound. Thus where it is desired that the thickness of winding on the bobbin should increase for a distance in leaving the base of the bobbin and then remain at a constant thickness, the blade-like element 160 may be relatively high opposite to the base portion of the bobbin and, as shown in Fig. 5, progressively decrease in height during the zone in which the thickness of the bobbin increases, thereafter remaining at a constant level during the winding of the main part of the bobbin.

A roller 165 mounted on a stud 166 on the thread guide arm 144 is adapted to engage suitable cam means hereinafter described to swing the traversing arm 144 about its pivot 141 and shift the eye 149 thereof to and beyond the plane of the serrated edge 61 of the hollow center 60. Such cam means are shown in Fig. 2 at 170. A horizontal angle 172 secured to the underside of the lower rail 12 supports a vertical angle 173 carrying a horizontal strip 174 to which is secured the cam strip 170 of appropriate shape to engage the roller 165 and shift the traversing arm to and beyond the plane of the serrated edge 61 of the hollow center 60.

On its way from the guide wires 51 (Fig. 4) to the traversing thread guide the yarn Y runs through the hooked end of the yarn detector 146 retaining this in the position of Fig. 5. The yarn detector consists essentially of a wire of bell crank shape pivotally mounted at 175 on the upper side

of the sleeve 103. An upturned arm 177 of the bell crank is adapted to engage a collar 178 on a rod 179 which connects the two legs 114 and 115 of the bracket 116. In case the yarn breaks and the detector 146 accordingly drops, its upturned extension 177 shifts the rod 179 and the bracket 116 to the right in Figs. 5 and 7 in opposition to a spring 180, causing the extension 177 to be withdrawn from under the latch 135 (Fig. 7) and thereby causing the mercury switch 130 to open and stop the motor 63.

The motor is stopped in a similar manner in case the bobbin becomes full by the thread-guide assembly striking the right hand leg 115 of the bracket 116 and shifting it to the right. Or, if desired, a further collar (not shown) similar to collar 178 may be adjustably clamped at the appropriate place on rod 179 and provided with a part adapted to extend into the path of the thread guide assembly so as to shift the rod 179 and bracket 116 and stop the motor whenever the thread-guide assembly attains a predetermined place in its outward travel.

The lower portion of the head of the winding machine is preferably provided with a chute 200 adapted to receive the full bobbin discharged from between the centers 60 and 100 and having a rounded bottom which as shown in Figs. 4 and 5 slopes downwardly toward the outer side of the winding unit. In order to detain the bobbin thus discharged the chute is provided with a door 201 at its larger end as shown in Fig. 6. A finger 205 may be adjusted vertically on the hinge pin 204 of the door 201 by being engaged in any one of several holes 206 of the door. This finger then is adapted to be struck and detained by a pin 207 (Fig. 4) appropriately positioned adjacent to the path of travel of the winding units. A number of receptacles 208 are preferably provided to receive bobbins discharged from the several units. Adjacent each one of these receptacles there is preferably provided an upright 209 having holes 210 for the reception of such a pin 207. Pins 207 are then located at different levels on the uprights 209 corresponding to the different receptacles 208 and as each such pin 207 encounters a finger 205 at the appropriate level on the door of the traveling unit, such door is then caused to open and discharge its bobbin from its chute into the corresponding receptacle 208. Thus by locating the fingers 205 of various ones of the traveling units at different levels and by providing appropriately located pins 207, the products of the various groups of winding units can be kept separate. For example, all those units winding a certain color of yarn can be caused to discharge into the same receptacle 208.

Referring to Figs. 1, 4 and 9, the machine includes an elevated hopper 290 adapted to hold a large number of empty bobbins which can be dumped into the hopper indiscriminately. As shown in Figs. 1 and 9, the bottom of the hopper slopes downwardly to form a central trough. Mounted for vertical movement up through the bottom of the trough are a pair of plates 292, 292 held apart by suitable spacer elements 293 a distance such that these plates 292, 292 can receive between them the body portions of bobbins (exclusive of the heads), the spacer elements 293 terminating far enough below the upper edges of plates 292 to permit the retained bobbins to clear the spacer elements. The bobbin-taking element comprised of the plates 292, 292 and spacer elements thus may be said to present a recessed face

to the mass of bobbins in the hopper. As shown in Fig. 4 where the plates 292, 292 have reached their uppermost position these plates then project somewhat above the top of the bobbin-holding space of the hopper 290. The upper edges of the plates 292, 292 slope downwardly toward the winding units of the machine, enabling empty bobbins, held by their heads between the plates 292, 292, to slide downwardly off the plates 292, 292 through a suitable slot in the left side of the hopper as shown in Fig. 4 and onto suitably positioned stationary guide rods 296, which form part of a bobbin magazine adapted to supply bobbins to the winding units in substantially the manner described in Patent No. 2,160,810.

The plates 292, 292 which may carry rollers 294, which run in channels 295 located at opposite sides of the hopper, are lowered so that their upper edges lie below some or all of the mass of empty bobbins in the hopper 290, then rise carrying with them some of the empty bobbins of which the body portions have dropped down in between the plates 292, 292. Practically every time the plates 292, 292 rise they thus carry with them one or several bobbins taken from the mixed-up mass of bobbins in the hopper and now arranged hanging vertically, suspended by their heads in position for delivery to the magazine.

For raising and lowering the plates 292, 292 (which may be suitably counterbalanced by a suitable weight not shown) there may be provided an electric motor (not shown) connected by a belt 300 to a reduction gear unit 301 which through a worm 302 and worm wheel 303 drives a sprocket 304 and chain 305. A link 307 pivotally mounted at 308 on the plates 292, 292 is also pivotally connected at 309 to the chain 305 so as to follow the upward and downward movement of a link of the chain and raise and lower the plates 292, 292 accordingly.

With the traveling units of the machine running in the direction of the arrow X of Fig. 2 each winding unit will either have completed the winding of its package or the yarn will have broken by the time the winding unit reaches the cams 110 and 170. The speed of travel of the winding units along the machine is such that there will be time for each winding unit to complete the winding of a package in somewhat less than the full time required to travel around the machine. As explained above, completion of the package results in the traverse assembly forcing the bracket 116 and its extension 117 to the right in Figs. 5 and 7, allowing the mercury switch 130 to open and stop winding. Likewise breakage of the yarn before stoppage of winding operates through the feeler 146 (Fig. 5) to force the rod 179 and bracket 116 to the right and open the mercury switch in the same manner.

With the winding unit thus inactive the stationary cam 110 acts on the projection 107 of the rod 102, forcing the tail stock 101 outwardly and discharging the wound package into the chute 200. Almost at once the roller 165 on the thread guide assembly strikes the stationary cam 170 and is moved by it to the left in Figs. 5 and 7. During the first part of this movement of the roller 165 the traversing arm 144 is shifted to the left about its pivot 141 and during the remainder of this movement the thread guide assembly is moved to the left carrying the yarn eye 149 to and beyond the vertical plane of the hollow head 60.

Pivoted in a sleeve 340 on one flange 151 of 75

the yoke 150 of the thread guide assembly is a double crank, the upper arm 341 of which extends into a cam slot 342 on the thread guide arm and the lower arm 343 of which lies below the level of a bobbin in winding position and carries a hook 344 at its outer end. A spring 345 reacts on the double crank to keep it normally in the position of Figs. 5 and 7. Swinging of the thread guide arm 144 to the left in opposition to the spring 345 turns the double crank and causes its hook 344 to swing and engage the run of yarn extending down from the eye 149 to the discharged bobbin in the chute 200. This swinging movement of the hook and the shifting movement of the thread guide assembly to the left causes this hook to carry the yarn over to and slightly beyond the plane of the hollow head 60.

Held in position across the hollow head 60 by the eye 149 above the head 60 and by the hook 344 below the head, the yarn is then ready to be engaged by a new bobbin.

At this point the traveling winding unit has reached the magazine 112. Then due to the termination of the cam surface 110a (Fig. 2) the tail stock 101 is allowed to move inwardly and the hollow center 100 grasps the small end of a bobbin in the magazine 112 forcing the outer end of the bobbin against the thread held across the hollow center 60, as explained in Patent No. 2,160,810.

At this point the yarn extending from the hollow center 60 down to the discharged bobbin in the chute 200 is engaged by a scissors knife 350 (Fig. 1) which as shown in detail in Fig. 12 is pivotally mounted at 351, is normally held open by a spring 352 and carries an extension 353 which is actuated by the passing winding unit to cut the yarn. Soon after the cutting of the yarn, winding is started on the unit. The extension 117 being in its restored position of Fig. 7 but the latch 135 being now below instead of above the extension 117, the mercury switch 130 is tilted to a closed position by contact of the arm 131 (Fig. 6) with a pin 355 (Fig. 1). The pivoted latch 135 is thereby raised up above the extension 117, latching the switch closed until either the yarn breaks or the next package is completed.

At the outset of the winding it is desirable to wind a starting bunch near the head end of the bobbin. In the illustrated machine this is accomplished in an improved manner by continuing the cam 170 beyond the magazine with a surface 170a so positioned as to allow the roller 165 to move somewhat toward the tip of the bobbin from its extreme position during the transfer of the bobbins. The surface 170a, which is continued for a distance corresponding to the amount of yarn that is to be wound in the bunch, temporarily detains this roller 165 against partaking of the full stroke of traverse of the traverse rod, as shown in Figs. 24 and 25. Operation of the traverse assembly including the plate 140 imparts an oscillating movement to the thread guide arm 144 about this roller 165 thus providing a short stroke of traverse appropriate to wind a narrow bunch of yarn near the base of the bobbin. When the end of the cam surface 170a is reached, normal reciprocating movement of the thread guide arm is resumed.

It will be understood that the machine may have any desired number of travelling units, for example twenty, all conveyed around the machine by the chain 14'. The units are preferably connected electrically by conductor wires 250 and

251 which travel around the machine in a loop with the several units. Referring to Fig. 2, on a given unit an electrical circuit is established between the wire 251, the mercury switch 130, the motor 63 and back to the wire 250.

A reel 255 centrally located in the machine and one or more double conductor wires 257 extending from the reel to the travelling wires 250 and 251 serve to transmit current to these travelling wires and the several units. As shown in Fig. 3, the reel is mounted on a hollow shaft 258 which turns in suitable ball bearings 259 and 260 in cross members of the frame. The reel as a whole is thus enabled to turn with the one or more double wires 257 that connect it to the travelling wires 250 and 251. A casing 260 for the reel turns with the hollow shaft 258 and is provided with one or more openings 261 for the one or more double wires 257. A drum 263 rotatably mounted in ball bearings 264 and 265 on the hollow shaft 258 is adapted to wind up the wires 257 under a light tension induced by a spiral spring 266 which is connected to the casing and to the drum, the spring and drum permitting the wires 257 to be payed out as necessary to allow the wires 257 to accompany their points of attachment to the travelling wires 250 and 251. The wires 257 at their ends which are fastened to the drum 263 are connected to slip rings 270 and 271 which receive current from stationary brushes 272 and 273 connected to a suitable source of current.

In the modification of Figs. 13 to 23, many parts of the machine are similar to those of the machine of Figs. 1 to 12, and hence will not be further described but merely designated by the same reference characters.

Referring to Figs. 13 and 14, the bobbin hopper 290 in this machine is located symmetrically of the long axis of the machine, between the opposite straight portions of track. An inclined slide in the form of spaced bars 400 is adapted to receive the bobbins which slide off the inclined upper edges of the plates 292, 292, and guide them to a position over the place of supplying the bobbins to the travelling units.

As shown in Fig. 21, the bobbins, hanging by their enlarged ends from the inclined bars 400, are detained by fingers 401 and 402 mounted on a shaft 403, the fingers being spaced apart a distance corresponding to the thickness of the enlarged base of a bobbin and being disposed at an angle to each other on shaft 403 in such relation that rotation of shaft 403 which moves finger 401 out of its bobbin-supporting position, also moves the other finger 402 into its bobbin-supporting position.

Rotation of the shaft 403 by a crank arm 404, rod 405 and crank 406 when the crank 406 is engaged by a pin 407 on a passing winding unit results in finger 401 turning with shaft 403 so as to move out of contact with the endmost bobbin and thereby releasing it (the other bobbins on the bars 400 then being retained by the finger 402 which is rotated by shaft 403 so as to move in to support these other bobbins). One bobbin is thus allowed to slide off the ends of bars 400. When the shaft subsequently returns to its normal position, finger 402 is thereby turned to a position to release the bobbins and allow the stack to be retained by the finger 401.

A pair of plates 409, spaced apart to receive the body portion of a bobbin between them then receive the bobbin discharged by the finger 401, allowing the enlarged base portion of the bobbin to slide down to the left in Fig. 21 from the upper

dotted line position through the lower dotted line position.

Fingers 412, 412, and 413, 413, on shafts 416 and 417 respectively, are positioned to retain the bobbin in a horizontal position at a level to be received by the centers 60 and 100 of a passing winding unit. As will be seen in Fig. 21, a bobbin sliding down the inclined edges of plates 409 has its tip end portion detained by the right hand set of fingers, and is thereby deflected and turned to its final horizontal position. The left hand set of fingers are located so as to engage the bobbin near its enlarged base end, thereby insuring that this end of the bobbin will be far enough to the left in Fig. 21.

Referring to Figs. 16 and 18, the travelling winding unit is provided with a vertically disposed plate 420 of which the main portion lies in a plane close to the plane of the face of the hollow center 60. This plate 420 reaches the bobbin retaining means 412, 413 before the center 60, in time to check the movement to the left of a bobbin being delivered to the fingers 412, 413 in Fig. 21. Thus this plate 420, acting in conjunction with the left set of fingers of Fig. 21, positions the new bobbin axially as well as vertically for reception by the bobbin holding centers of the travelling unit.

Shafts 416 and 417 which carry the fingers 412, 412 and 413, 413, also carry levers 430 and 431 which are yieldingly connected by a spring 432, and these levers and the fingers are normally held in the full-line position of Fig. 22 by a further spring 434. When a bobbin, after being grasped by the centers 60 and 100 of a winding unit is carried in the direction of the arrow X of Fig. 22, the fingers 412 are swung by the bobbin to the dotted line position of Fig. 22, the fingers 413 allowing the bobbin to pass out from between both sets of fingers. In the swinging of fingers 412, fingers 413 are carried to their dotted line position of Fig. 22, due to the spring connection between levers 430 and 431, and in their dotted line position allow the winding unit to pass without interference.

The modification of Figs. 13 to 23 shows an improved arrangement of stationary conductor rails for carrying current to the motors of the travelling units. Referring to Figs. 14 and 15, three vertically arranged conductor rails 440, 441 and 442 are provided, spaced from each other and from the rail 11 by short pieces of insulating material, with the upper edges of these conductor rails slightly below the top of rail 11. Brackets 445, screwed to rail 11 at intervals along the machine, clamp the conductor rails and pieces of insulating material firmly in place. In between the brackets 445 the spaces between the vertically disposed rails are open, which has the advantage that fly and waste can drop down past the rails, leaving their top surfaces free. Moreover, the vertical arrangement of the rails side by side around the track of the machine has the advantages that the flat rails may readily be bent to the required shape, and when in place, are readily accessible for connection to the current supply.

On each travelling unit, a set of three brushes 450, adapted to contact with the respective conductor rails are vertically slidably in a suitable frame 451 of insulating material. Each brush 450 is connected at its top to a suitable binding post by a resilient wire 453 passing through its top portion and urging the brush down into contact with its associated conductor rail. All three brushes may be simultaneously lifted by a hori-

zontal pin 460 (of insulating material) carried by a boss 462 on an arm 461 of a bell crank 461, 463, the pin engaging beneath the resilient wires 453 and being pressed upwardly by a coil spring 463a. The other arm 463 of the bell crank is normally latched behind the left end portion of a slideable rod 467 (Figs. 15, 16 and 18) this rod corresponding in its motor controlling functions to the longitudinally shiftable rod 179, bracket 116 and extension 117 of the machine of Figs. 1 to 12. Shifting of the rod 467 to the right in Figs. 15 and 18 (either by the thread guide having progressed to the desired position corresponding to the completed filling-wound bobbin, or the winding unit being about to reach the bobbin-changing apparatus, both as described herein-after) thus releases the crank arm 463, allowing the spring 463a to raise the brushes 450 off the conductor rails and stop the motor. At the position for starting winding, a stationary roller 480 (Figs. 14 and 17) engages the boss 462 (Fig. 15), restoring the bell crank 461, 463 to its normal position causing the brushes to make contact with their rails, and causing the upper arm 463 of the bell crank to become latched again behind the end portion of rod 467.

As in the machine of Figures 13 to 23, the non-traveling mechanism for controlling the positions of the thread guides, opening and closing the bobbin holding centers, controlling the winding of a starting or reserve bunch, and opening the bobbin chute doors, as well as certain other parts of the mechanism, are located on a stationary frame outside of the tracks 11 and 12. As shown in Figures 13 and 14, suitable uprights 470 carry a horizontal member 471 upon which the bobbin delivering plates 409, 409 are mounted, and also an angle piece 473 shaped as shown in Figure 14 and having with the angle pieces 473a and 511 the general function of the strip 170 of Figure 2; that is, to shift the traversing thread guide to starting position and subsequently control the position of the thread guide in the winding of the starting bunch.

Referring to Figures 18, 19, and 20, the thread guide assembly includes an upper yoke 480 and a lower yoke 481, the legs of each of these yokes loosely engaging the traverse rod 66. A block of friction material, such as cork 483, cut out to fit the round traverse rod 66 occupies the space above the traverse rod and within the upper portion of the upper yoke 480, and is pressed yielding against the traverse rod 66 by a spring 485 contained in the upper yoke 480. By this means, the traverse assembly frictionally grips the traverse rod 66, but may be advanced relatively to the traverse rod. The upper yoke 480 carries the thread guide arm 144, which in this instance is not pivotally connected thereto, and the lower yoke 481 carries the combined yarn feeler 155 and arm 156 which carries the down-turned edge portion 157. As in the embodiment of Figures 1 to 12, when the yarn feeler 155 contacts with the yarn wound on the bobbin and is consequently forced away from the axis of the bobbin, the element 155, 156 is tilted about the traverse rod 66, and the down-turned edge portion 157 brought into contact with one of the teeth 161 of the blade-like element 160. The thread guide assembly is then detained against further movement toward the left in Figure 18, the cork 483 allows the traverse rod 66 to move relative to the thread guide assembly, and the thread guide assembly is thus advanced axially with respect to the traverse rod. Any suitable spring means may be

employed to control the pivotally mounted member 155, 156. For instance, a light spring 490 mounted on the thread guide arm 144 may be employed to urge the element 155, 156 in a counterclockwise direction in Figure 19.

A down-turned extension 492 on the thread guide arm, offset somewhat to the right from the eye 149, is adapted to engage an adjustable collar 493 on the rod 467, and when the package 10 attains the desired length, will shift this collar and rod somewhat to the right and thereby unlatch the crank arm 463, thereby causing the motor to be de-energized, as spring 499 (Fig. 15) acts on the right-hand end of rod 467 to restore it to the left into latching position.

In normal operation, the package will have been completed and the rod 467 will have been tripped to de-energize the motor by the time the traveling unit reaches the bobbin changing apparatus of Figure 14. However, to insure that no winding unit reaches this apparatus with its motor running, a stationary cam 500 (Figs. 14 and 15) is provided in position to engage and shift the collar 493 to the right in Figure 15 to trip the rod 467 and stop the motor.

In the embodiment of Figures 13 to 23, the outer center 100 is mounted on a plunger 100a which is slideable in an out-board bracket 100b, this bracket being fixedly secured to a horizontal bar 100c rigid with the frame 40 of the winding unit. The outer center 100 is mounted on a plunger 100a which is slideable in and out of the stationary bracket 100b, is normally forced against the winding bobbin by a spring (not shown) in the bracket 100b, and may be retracted by a bell crank 100d of which one arm engages the plunger 100a within the bracket. When the winding unit reaches the bobbin changing apparatus shown in Figure 14, the outstanding arm of the bell crank 100d engages a stationary angle piece 590, and is moved thereby into the dotted line position of Figure 18, releasing the bobbin. At the right-hand end of the angle piece 590, the bell crank 100d is released, and the plunger 100a and center 100 return to their positions of Figure 18, thus to engage the bobbin held by the fingers 412, 412 and 413, 413.

Referring to Figures 14 and 23, a stationary bracket 592 located near the beginning of angle bar 590 carries a pivotally mounted finger 593 normally hanging downwardly in the path of the tip portion of a bobbin carried by the approaching traveling winding unit. A bent tail portion 593a on the finger 593 is adapted to seat slidably on top of the bar 100c of the traveling unit, thereby preventing the finger 593 from being swung upwardly past the dotted line position of Figure 23. Thus when the tip portion of a bobbin indicated at B in Fig. 23 encounters the finger 593, the finger is free to be turned to the dotted line position where it is then locked and forces the bobbin downwardly, thus insuring that when the center 100 opens, the bobbin will not be held in winding position by the yarn or the friction 65 of the base center 60.

Upon encountering the angle bar 590 and finger 592 and having its full bobbin discharged into its chute 200, the winding unit has its traverse assembly shifted to the left in Figures 15 and 18 to carry the thread guide eye 149 beyond the vertical plane of the base center 60, this being accomplished by the cam-shaped angle 473 (Figs. 14 and 15) which engages with the roller 165 on the thread guide assembly. The run of yarn extending downwardly from the eye

149 to the discharged bobbin in chute 200 is engaged by a stationary cam surface 502 (Fig. 14) which deflects this run of yarn over to the base center 60, thus in conjunction with the eye 149, laying the yarn across the hollow center. Mounted on the traveling unit (Fig. 18) is a plate 507 having a cam-like plow or guiding surface engaged by this lower run of yarn and directing it toward the middle of the hollow center 60. As shown in dotted lines in Figure 18, and in full lines in perspective in Fig. 18a, the plate 507 has a shoulder 508, behind which the yarn is adapted to engage, this shoulder being thin and knife-like and in close proximity to the plane of the rim of the hollow center 60. When a bobbin is clamped between the centers and is started to rotating, the rotating center tensions the yarn against this shoulder portion 508 and immediately severs it close to the hollow center.

It has been mentioned that the eye 148 is moved past the plane of the hollow center 60. In order to permit this, the yarn feeler 155 is shifted away from the axis of winding so as to permit it to pass over the hollow center 60. As shown in Figure 15, a bracket 510 on the frame of the winding unit is provided with a cam surface 511 adapted to engage the portion of the traverse assembly carrying the down-turned edge portion 157 so as to force this downwardly when the cam surface 511 is encountered, swinging the element 155, 156 in a clockwise direction in Figure 19 and permitting the feeler 155 to pass over the hollow center 60.

As has been mentioned in connection with the machine of Figures 1 to 12, blade-like element 160 is adapted to serve as a forming plate to control the shape of the bobbin wound. As shown in Figures 15 and 16, this plate is further formed in sections 160a and 160b which are slotted and secured to the side of bar 100c by bolts, so that when desired, the sections of this element 160 may be raised or lowered, toward or from the edge portion 157 of member 156, or one section inclined to a greater or lesser extent to the other so as to adjust this element for the formation of bobbins of different shapes.

In the embodiment of Figures 13 to 23, the thread guide assembly is returned to bunch-winding position by a down-turned flange on an inclined section of angle bar 473a (Figs. 14 and 15) and the formation of the width of bunch is controlled by limiting the extent of reciprocation of the thread guide assembly between a down-turned flange of a section of angle bar 473b (Fig. 14) and a further down-turned flange of an angle piece 511, these two flanges together forming a relatively narrow zone in which the roller 165 of the thread guide assembly can reciprocate to wind a bunch as shown in Figs. 26 and 27.

The machine of Figures 13 to 23 may be provided with mechanism for opening the doors of the several winding units at different predetermined places in order to segregate the products of the several units or groups of units as in the machine of Figures 1 and 12, and this mechanism need not be further described. Referring to Figure 14, a pin or plate 520 is shown in position to open the chute door of a winding unit at that place. In order to keep the door open for a somewhat longer time, there may then be provided a stationary plate 521 adapted to retain the door open while the unit is passing any suitable receptacle for the wound bobbin.

In connection with the use of stationary conductor rails, such as those indicated at 440, 441

and 442, it is desirable to keep the travelling unit in close contact with the upper track rail 11 at all times. In order to establish this both on the straight and the curved portions of the track, the unit of Figures 13 to 23 is provided with three vertical track-engaging rollers 530 and 531 on the outside of the track and as shown in dotted lines in Figure 16, roller 532 on the inside of the track, these rollers being positioned to engage the track 11 closely. Then on the curved portion of track 11, the thickness of this track is increased as shown in the left portion of Figure 14 in an amount such that in passing around this curved portion of the track, neither the inner roller 532 nor the outer rollers 530 or 531 will lose contact with the track. With this arrangement, the conductor rails 440, 441, and 442 may be carried around the semi-circular ends of the machine, and the brushes of the travelling units may be held in accurate alignment with the conductor rails both on the curved and straight portions of the track.

We claim:

1. A winding machine having therein means for rotating a winding package, a reciprocating traverse bar, a thread guide assembly on the traverse bar and frictionally related thereto and driven thereby, a package-feeler on the thread-guide assembly, and means controlled by the feeler for detaining the thread-guide assembly against movement in one direction by the traverse bar while permitting the traverse bar to slide with respect to the thread-guide assembly, thereby to advance the traverse assembly in accordance with the growth of the winding package.
2. A winding machine having therein means for rotating a winding package, a reciprocating traverse bar, a thread guide assembly on the traverse bar and frictionally related thereto and driven thereby, means adapted to restrain the thread guide assembly against movement toward one end of the winding package, and means on the thread-guide assembly responsive to the growth of the winding package for actuating said restraining means while permitting the traverse bar to slide with respect to the thread-guide assembly.
3. A winding machine having therein means for rotating a winding package, a reciprocating traverse bar, a thread guide assembly on the traverse bar and frictionally driven thereby, a toothed element not partaking of the traversing movement of the traverse assembly, means on the thread-guide assembly adapted to engage said toothed element to check movement of the thread-guide assembly in one direction, and a package feeler for actuating said last-named means.
4. A winding machine having therein a traveling unit, a guideway therefor, and means for conveying the unit along the guideway, conductor rails extending along said guideway, electrically conducting plungers on the unit adapted to contact with the conductor rails, resilient means for urging the plungers into contact with the conductor rails, means for retracting the plungers to move them out of contact with the conductor rails, latch means for normally holding said plunger-retracting means ineffective, means for releasing the latch means, and relatively stationary means for resetting the latch means of a passing unit, thereby to restore electrical contact between the plungers of said unit and the conductor rails.

5. In a winding machine having a guideway and a traveling unit adapted to run thereon, a rail extending along the path of travel of the said unit, vertically disposed electric conductor bars extending side by side along said rail, short sections of insulating material between the bars, and brackets secured to the rail and clamping the conductor bars and insulating material together and securing the same to the rail, the upper edges of the conductor bars lying approximately in the same plane near but below the level of the upper surface of said rail, the said vertically disposed conductor bars affording ready access for connection to the current supply, and the space between said bars in between the brackets being open to permit dust and fly to fall therethrough.

6. A winding machine having therein a guideway, a winding unit adapted to travel along the guideway, the winding unit including a frame and two centers for holding a winding bobbin, a bracket for holding the outermost center, the center being axially movable in said bracket, a lever mounted in said bracket and connected to act on said center to shift the center outwardly away from the other center, and the machine including a relatively stationary element adapted to engage and turn said lever at a predetermined place in the path of travel.

7. A winding machine having therein means including a driven shaft for rotating a winding package, means for distributing the winding yarn on the winding package including a reciprocating element and a double-throw generally flat cam for reciprocating said element, a worm on said driven shaft and a worm wheel arranged to drive the cam therefrom the shape of the cam being such that the two throws of the cam are of different length.

8. A winding machine having therein means including a driven shaft for rotating a winding package, means for distributing the winding yarn on the winding package including a reciprocating element and a double-throw generally flat cam for reciprocating said element, a worm on said driven shaft and a worm wheel arranged to drive the cam therefrom the shape of the cam being such that the two throws of the cam are of different length, and being such that in each throw, movement of the thread guide is faster toward one end of the winding package than toward the other.

9. A winding machine having therein means including a driven shaft for rotating a winding package, means for distributing the winding yarn on the winding package including a reciprocating element and a double-throw generally flat cam for reciprocating said element, a worm on said driven shaft and a worm wheel arranged to drive the cam therefrom the shape of the cam being such that the two throws of the cam are of different length and being such that in each throw, movement of the thread guide is approximately twice as rapid toward one end of the winding package than toward the other.

10. A winding machine having therein means including a driven shaft for rotating a winding package, means for distributing the winding yarn on the winding package including a reciprocating traversing element and a double-throw generally flat cam for reciprocating said element, a worm on said driven shaft and a worm wheel arranged to drive the cam therefrom the shape of the cam being such that each stroke of motion imparted thereby to the traversing element is of a different length than the preceding stroke.

11. A winding machine having therein means for rotating a winding package, means for distributing the winding yarn on the winding package including a reciprocating element and a double-throw cam for reciprocating said element, the shape of the cam being such that the successive strokes of traverse imparted thereby to the reciprocating element have lengths approximately in the following ratio: $1\frac{1}{8}$, $1\frac{1}{2}$, $1\frac{5}{8}$ and $1\frac{1}{2}$.

12. A winding machine having therein means for rotating a winding package, means for distributing the winding yarn on the winding package including a reciprocating element and a double-throw cam for reciprocating said element, the shape of the cam being such that the successive strokes of traverse imparted thereby to the reciprocating element have lengths approximately in the following ratio: $1\frac{1}{8}$, $1\frac{1}{2}$, $1\frac{5}{8}$ and $1\frac{1}{2}$, the rate of speed of the reciprocating element being substantially faster on the strokes of unequal length than on those of equal length.

13. A winding machine having therein a traverse cam of generally flat shape, a reciprocating traverse bar actuated thereby, a casing for the cam, a removable cover for the casing, the casing being slotted to receive the reciprocating traverse bar, and the cover constituting a guiding surface for the said traverse bar.

14. A winding machine having therein means for rotating a winding package, a reciprocating traverse bar, a thread-guide assembly on the traverse bar, means for progressively advancing the thread-guide assembly along the traverse bar, means for automatically returning the thread-guide assembly from its position where winding of one bobbin is completed to the opposite end of its path of advance along the traverse bar, the machine having a frictional non-positive connection between the thread-guide assembly and the traverse bar both during the advance and the return of the thread-guide assembly.

15. A winding machine having therein a plurality of winding units and bobbin-supplying mechanism therefor, means for causing a relative movement between the winding units and bobbin-supplying mechanism, and a cam in position to contact with the yarns of the successive winding units and direct the yarn to one end of a new bobbin supplied by the bobbin-supplying mechanism.

16. A winding machine having therein a plurality of traveling winding units, and a bobbin-supplying mechanism adapted to act on the winding units in succession, and a stationary cam interposed in the path of the yarns of the winding units to direct the yarn to one end of a new bobbin supplied by the bobbin-supplying mechanism.

17. A winding machine having therein a hollow holder for holding the base end of a winding bobbin, a thread guide, means for discharging the wound bobbin from the holder, means for shifting the thread guide and yarn toward the holder, a cam-like plow positioned to engage the yarn moving toward said holder and center the yarn with respect to the holder, means for supplying a fresh bobbin to the holder, and said plow having a shoulder close to the plane of the face of the hollow holder, the said shoulder providing an edge against which the yarn can be severed close to the holder by rotation of the holder.

18. A winding machine having therein a holder for a winding bobbin, a traverse rod adapted to reciprocate, a thread guide assembly on the traverse rod, a package feeler and means controlled thereby to advance the thread guide as-

sembly along the traverse rod, means for shifting the thread guide assembly in the opposite direction to carry the yarn beyond the plane of the face of said holder, and means effective to move the package feeler away from the axis of winding of the package, permitting said feeler to pass said holder.

19. A winding machine having therein a holder for a winding bobbin, a traverse rod adapted to reciprocate, a thread guide assembly on the traverse rod, a package feeler and means controlled thereby to advance the thread guide assembly along the traverse rod, means for shifting the thread guide assembly in the opposite direction to carry the yarn beyond the plane of the face of said holder, and a cam effective when said package feeler nears the said holder to move the package feeler away from the axis of winding of the package, permitting said feeler to pass said holder.

20. A winding machine having therein a plurality of winding units each including a reciprocating traverse bar and a thread guide assembly thereon, means for moving the units in a predetermined path, means operative to supply new winding bobbins to the successive units, means operative at a predetermined place in the path of travel to constrain the thread guide of a winding unit to the winding of a relatively narrow starting or reserve bunch, and means for shifting the thread guide assembly of each winding unit in succession to a predetermined place along the axis of a bobbin where said bunch is to be wound.

21. A winding machine having therein a plurality of winding units each including a reciprocating traverse bar and a thread guide assembly thereon, means for moving the units in a predetermined path, means operative to supply new winding bobbins to the successive units, means operative at a predetermined place in the path of travel to constrain the thread guide of a winding unit to the winding of a relatively narrow starting or reserve bunch, and a non-travelling cam adapted to position each thread guide assembly at the place for winding such bunch.

22. A winding machine having therein means for rotating a winding package, a reciprocating traverse bar, a thread guide assembly on the traverse bar and frictionally driven thereby, and means effective at the start of winding of a new package to detain the thread guide assembly against partaking of the full stroke of traverse of the traverse bar, thereby to wind a starting or reserve bunch.

23. A winding machine having therein a holder for holding the base end of a winding bobbin, a thread guide, means for discharging the wound bobbin from the holder, means for shifting the thread guide to and beyond the plane of the face of the holder, a cam-like plow positioned to engage the yarn moving toward said holder, said plow having a shoulder close to and facing the plane of the face of said holder, and means, effective when the yarn is held across the holder by the thread guide and shoulder, for supplying a new bobbin to the holder.

24. A winding machine having therein a plurality of winding units each having winding bobbin holding means including a center for holding one end of a bobbin, means for causing the units to travel in a predetermined path, bobbin supplying means for delivering fresh bobbins to said centers of said units in succession, and a stop element on each unit and having a face in a plane close to the plane of the said center, said stop element co-

operating with a bobbin in said bobbin supplying means to position such bobbin for reception by the said center of said unit.

25. A winding machine having therein a plurality of winding units, means for causing said units to travel in a predetermined path, means adapted to retain a fresh bobbin in the path of travel of said units, said retaining means holding said bobbin releasably so as to permit a traveling winding unit to take said bobbin therefrom, means for causing the successive units to take a fresh bobbin from said bobbin retaining means, means for holding a plurality of fresh bobbins in readiness to be delivered to said bobbin retaining means but with said plurality of bobbins spaced from the bobbin retained in said bobbin retaining means, and means for releasing said fresh bobbins from said holding means one at a time to said bobbin retaining means, said releasing means operating in timed relation to the taking of bobbins from the bobbin retaining means by the traveling winding units.

26. A winding machine having therein a plurality of winding units, means for causing said units to travel in a predetermined path, means adapted to retain a fresh bobbin in the path of travel of said units, said retaining means holding said bobbin releasably so as to permit a traveling winding unit to take said bobbin therefrom, means for causing the successive units to take a fresh bobbin from said bobbin retaining means, means for holding a plurality of fresh bobbins in readiness to be delivered to said bobbin retaining means but with said plurality of bobbins spaced from the bobbin retained in said bobbin retaining means, and means controlled by passage of a traveling winding unit for releasing said fresh bobbins from said holding means one at a time to said bobbin retaining means.

27. A winding machine having therein a plurality of winding units each having means for holding a winding bobbin, means for causing said units to travel in a predetermined path, means adapted to retain a fresh bobbin in the path of travel of said units in position to be received by the bobbin holding means of a passing unit, means for causing the bobbin holding means to engage said bobbin when in said bobbin retaining means, said bobbin retaining means including fingers on opposite sides of the retained bobbin, the fingers on the two sides being pivotally mounted on separate pivots, and a connection between the fingers on the two sides whereby travelling movement of the bobbin engaged by the bobbin holding means of a travelling unit causes said fingers to open and release said retained bobbin to the travelling unit.

28. A winding machine having therein a plurality of winding units each having means for holding a winding bobbin, means for causing said units to travel in a predetermined path, means adapted to retain a fresh bobbin in the path of travel of said units in position to be received by the bobbin holding means of a passing unit, means for causing the bobbin holding means to engage said bobbin when in said bobbin retaining means, said bobbin retaining means including fingers on opposite sides of the retained bobbin, the fingers on the two sides being pivotally mounted on separate pivots, and a yielding connection between the fingers on the two sides whereby travelling movement of the bobbin engaged by the bobbin holding means of a travelling unit causes said fingers to open and release said retained bobbin to the travelling unit.

29. A winding machine having therein a winding unit including opposite centers one of which holds the enlarged base end and the other of which holds the smaller tip end of a winding bobbin, an inclined slide comprising spaced members between which bobbins are adapted to hang by their enlarged ends, a second inclined slide adapted to receive a bobbin from the first-mentioned slide, means for retaining a bobbin in a generally horizontal position beneath the second slide in position to be engaged by said opposite centers of the winding unit, and means for releasing bobbins one at a time from the first-mentioned slide.

30. A winding machine having therein a winding unit including opposite centers one of which holds the enlarged base end and the other of which holds the smaller tip end of a winding bobbin, an inclined slide comprising spaced members between which bobbins are adapted to hang by their enlarged ends, a second inclined slide adapted to receive a bobbin from the first-mentioned slide, and means adapted to act on a bobbin sliding down the second slide to turn the bobbin to a generally horizontal position and retain it for reception by the centers of the winding unit.

31. A winding machine having therein a plurality of winding units each having winding bobbin holding means including a center for holding the enlarged base end of a bobbin, means for causing the units to travel in a predetermined path, bobbin supplying means for delivering fresh bobbins to said centers of said units in succession, a stop element on each unit, and having a face in a plane close to the plane of said center, and the bobbin supplying means including fingers adapted to hold the body of the bobbin near its enlarged base end, thereby to position the bobbin axially for reception by the winding unit.

32. A winding machine having therein a plurality of winding units, means for causing the units to travel in a predetermined path, a plurality of receptacles for wound bobbins, bobbin chutes on the several winding units adapted to discharge wound bobbins to said receptacles, and means for causing the chutes of certain winding units to discharge to predetermined corresponding receptacles.

33. A winding machine having therein a plurality of winding units, means for causing the units to travel in a predetermined path, a plurality of receptacles for wound bobbins, bobbin chutes on the several winding units adapted to discharge wound bobbins to said receptacles, doors normally closing the chutes of said units, and means for selectively opening the doors opposite to predetermined corresponding receptacles.

34. A winding machine having therein a plurality of winding units, bobbin supplying mechanism adapted to supply fresh bobbins to the several winding units in succession, said bobbin supplying mechanism including a slide down which the fresh bobbins are adapted to move to position to be received by the winding units, means for causing relative traveling movement between the winding units and said slide such that the winding units are presented successively thereto and means for automatically placing fresh bobbins on the slide.

35. A winding machine having therein bobbin feeding mechanism for empty bobbins comprising a hopper adapted to receive empty bobbins

in a mixed up state, and a bobbin-taking element adapted to move through a mass of bobbins in the hopper, the bobbin-taking element presenting a recessed face to the mass of bobbins, the recess being wide enough to receive the body portion of the bobbin but insufficient in width to receive the enlarged base portion thereof.

36. A winding machine having therein bobbin feeding mechanism for empty bobbins comprising a hopper adapted to receive empty bobbins in a mixed up state, and a bobbin-taking element adapted to move vertically through a mass of bobbins in the hopper, the bobbin-taking element presenting a recessed face to the mass of bobbins, the recess being wide enough to receive the body portion of the bobbin but insufficient in width to receive the enlarged base portion thereof.

37. A winding machine having therein bobbin feeding mechanism for empty bobbins comprising a hopper adapted to receive empty bobbins in a mixed up state, and a bobbin-taking element adapted to move through a mass of bobbins in the hopper, the bobbin-taking element presenting a recessed face to the mass of bobbins, the recess being wide enough to receive the body portion of the bobbin but insufficient in width to receive the enlarged base portion thereof, said bobbin-taking element having an upper edge inclined to the horizontal, so that bobbins taken thereby slide along the upper edge held by their enlarged base portions.

38. A winding machine having therein bobbin feeding mechanism for empty bobbins comprising a hopper adapted to receive empty bobbins in a mixed up state, and a bobbin-taking element adapted to move through a mass of bobbins in the hopper, the bobbin-taking element presenting a recessed face to the mass of bobbins, the recess being wide enough to receive the body portion of the bobbin but insufficient in width to receive the enlarged base portion thereof, said bobbin-taking element having an upper edge inclined to the horizontal, so that bobbins taken thereby slide along the upper edge held by their enlarged base portions, and a slide positioned to receive bobbins from the bobbin-taking element.

39. A winding machine having therein means for rotating the winding packages, a reciprocating traverse rod, a thread guide assembly on the traverse rod and frictionally driven thereby, the thread guide assembly including a thread guide arm pivotally connected to the thread guide assembly and normally reciprocating with the thread guide assembly and means for detaining the thread guide arm against partaking of the full stroke of reciprocation of the thread guide arm at the start of winding of a new package, while permitting oscillation of the thread guide arm about its pivot, thereby to traverse the winding yarn in the form of a starting or reserve bunch.

40. A winding machine having therein means for rotating a winding package, a reciprocating traverse bar, a thread guide assembly on the traverse bar and frictionally driven thereby, a toothed element not partaking of the traversing movement of the traverse assembly, cooperating means on the traverse assembly movable into and out of engagement with said toothed element, and a package feeler adapted upon movement away from the axis of the package to cause said cooperating means to move toward engagement with said toothed element, said toothed element hav-

ing a non-uniform height thereby to control the shape of the winding bobbin.

41. A winding machine having therein means for rotating a winding package, a reciprocating traverse bar, a thread guide assembly on the traverse bar and frictionally driven thereby, a toothed element not partaking of the traversing movement of the traverse assembly, cooperating means on the traverse assembly movable into and out of engagement with said toothed element, and a package feeler adapted upon movement away from the axis of the package to cause said cooperating means to move toward engagement with said toothed element, said toothed element comprising a plurality of sections adjustable with respect to each other to vary the shape of the bobbin.

42. A winding machine having therein means for rotating a winding package, a reciprocating traverse bar, a thread guide assembly on the traverse bar and frictionally driven thereby, a toothed element not partaking of the traversing movement of the traverse assembly, cooperating means on the traverse assembly movable into and out of engagement with said toothed element, and a package feeler adapted upon movement away from the axis of the package to cause said cooperating means to move toward engagement with said toothed element, said toothed element being

adjustable toward and from the said cooperating means to vary the diameter of the bobbin.

43. A winding machine having therein a plurality of winding units adapted to travel around the machine, and a rail having straight and semi-circular portions for guiding said units in their travel, each unit having one vertically arranged roll running on the inside face of said rail and two vertical rolls running on the outside face of said rail, the rail being of increased thickness at its semi-circular portions as compared to its straight portions to maintain approximate contact of all three of said rolls with the rail in both the straight and semi-circular portions.

44. A winding machine having therein a plurality of traveling winding units each including a holder for the base end of a winding bobbin, a bobbin-supplying mechanism adapted to act on the winding units in succession, a stationary cam interposed in the path of the yarn of the winding units to direct the yarn to one end of a new bobbin supplied by the bobbin-supplying mechanism and a cam-like plow on each unit positioned to engage the yarn moved by said stationary cam and center said yarn with respect to said holder.
